UNITED STATES PATENT OFFICE.

JAMES F. MACWILLIAM, OF HUBBARDSTON, MASSACHUSETTS.

NOZZLE.

No. 902,309.

Specification of Letters Patent.

Patented Oct. 27, 1908.

Application filed December 2, 1903. Serial No. 183,471.

To all whom it may concern:

Be it known that I, JAMES F. MACWILLIAM, a citizen of the United States, residing at Hubbardston, in the county of Worcester 5 and State of Massachusetts, have invented a new and useful Nozzle, of which the following is a specification.

This invention relates to that class of nozzles which are employed on hose pipes, or 10 other fixtures, and especially to that class of nozzles which are employed in connection with fire extinguishing apparatus.

The especial object of this invention is to provide a strong, simple, and inexpensive 15 nozzle which will insure a positive shutting off of the stream, or which can be set either to be wide open or to produce spraying effects, and in which the parts are not liable to become stuck or wedged when the nozzle 20 is allowed to stand for considerable periods of time.

To these ends, this invention consists of the nozzle and of the combinations of parts 25 therein as hereinafter described and more particularly pointed out in the claims at the end of this specification.

In the accompanying drawing, Figure 1 is a side view of a nozzle constructed according to this invention partly broken away to show 30 the parts in closed position; Fig. 2 is a longitudinal sectional view of the same showing the parts in open position, and Fig. 3 is a transverse sectional view taken on the line 3—3 of Fig. 2.

In the use of nozzles in connection with 35 hose-pipes or other apparatus, and particularly in the use of nozzles in connection with fire extinguishing apparatus, it is essential to provide a construction having simple 40 and directly operative parts, so that the nozzle may be used efficiently even when the same has not been operated for considerable lengths of time. For this reason in nozzles 45 of this class it is desirable that the use of all leather or rubber packings inside the nozzle be dispensed with.

In a nozzle constructed according to my 50 invention I have provided a simple and direct cut off action without the use of leather or rubber packings, and I have also designed the parts of my nozzle so that the same may be made at comparatively little cost.

Referring to the accompanying drawing and in detail, a nozzle constructed according 55 to this invention as herein illustrated com-

prises a body portion 10. The body portion 10 is provided with internal threads near its end, and a hose-pipe H may be connected to the nozzle through an ordinary coupling C which is threaded into the end of the body 60 portion 10 and bears against a packing-washer D in the ordinary manner. Extending transversely across the chamber inside the body portion 10 is a bridge-piece 11, and cast into or otherwise secured in the bridge-piece 11 is a soft metal bearing piece 12, which forms a valve seat. The bearing piece 12 is provided with an annular groove or recess 120 and a central projection or abutment 121.

Coöperating with the bridge piece 11 is an outlet tube 13 which is threaded into the end of the body portion 10, and is provided with a tapering or conical end 16, which may be screwed down into the annular groove in the 75 soft metal bearing-piece 12 when it is desired to throttle the stream, and which may be seated tightly against the soft metal piece 12 when it is desired to close the nozzle as shown in Fig. 1. The ordinary gland 14 is threaded 80 on the body portion 10, and serves to hold the packing 15 in place. On the end of the outlet tube 13, I provide an operating handle 17, and a nozzle tip 19.

As shown most clearly in Fig. 3, the operating handle or hand-wheel 17 is threaded 85 on the outlet tube 13, while the nozzle tip 19 is also threaded thereon, being provided with a wrench section 20 for this purpose. By means of this arrangement of operating handle 17 and nozzle tip 19 it will be seen that the nozzle tip 19 serves as a lock-nut for holding the hand-wheel 17 in place.

In the use of a nozzle as thus constructed 95 it will be seen that when the valve is closed, air will be excluded from the inside of the valve-casing, and that the water or other fluid from the pipe H will fill the entire nozzle body and will be ready to enter the outlet tube the instant the nozzle is opened. In 100 addition to this, the pressure of water inside the body portion of the nozzle will serve to keep the packing 15 constantly wet and pressed out against the cap 14, so that this packing will never dry up and allow leakage 105 when the nozzle is opened. A still further advantage in the use of this construction is due to the fact that when the outlet tube is unscrewed, the end of the outlet tube at once begins to leave the valve-seat, so that even 110

if there is grit or dirt within the nozzle, the valve-seat will not be scratched or grooved.

A nozzle constructed according to this invention is also especially adapted for use on fire extinguishing apparatus, because, even when the nozzle has not been used for a long period of time, the relatively small area of the valve-seat and the relatively large size of the hand-wheel will give sufficient leverage so that corrosion will not be liable to stick the parts together to prevent the nozzle readily being opened.

Changes may be made in the outline and proportions of nozzles constructed according to this invention without departing from the scope thereof as expressed in the claims. I do not wish, therefore, to be limited to the special construction I have herein shown and described, but

20 What I do claim and desire to secure by Letters Patent of the United States is:—

1. As an article of manufacture, a nozzle comprising a body portion having a valve-seat, an outlet tube mounted in the body portion, its end being adapted to seat against the valve-seat to close the nozzle, a hand-wheel threaded on the outlet tube, and a nozzle tip also threaded onto the outlet tube and forming a lock nut for holding the hand-wheel in place.

2. As an article of manufacture, a nozzle comprising a body portion having a bridge, an outlet tube threaded into the body portion so that its end may be seated against the bridge to close the nozzle, a hand-wheel threaded on to the outlet tube, and a nozzle tip also threaded on to the outlet tube and

forming a lock-nut for holding the hand-wheel in place.

3. As an article of manufacture, a nozzle 40 comprising a body portion having a bridge, and having screw threads at one end for receiving a coupling to connect the nozzle with the hose, a soft metal piece secured in the bridge of the body portion and having an 45 annular groove with a central projection, an outlet tube threaded into the opposite end of the body portion and having a tapering end which may be seated in the groove of the soft metal piece, a hand-wheel threaded on 50 to the outlet tube, and a nozzle tip also threaded on to the outlet tube, and serving as a lock-nut for fastening the hand-wheel in place.

4. As an article of manufacture, a nozzle 55 comprising a body portion having a chamber therein provided with a bridge spaced from both ends of the chamber, said body portion having means at one end to receive a coupling to connect the nozzle with a hose, a soft 60 metal piece mounted on the bridge and having an annular groove, an outlet tube adjustably mounted in the opposite end of the body portion and having a tapering end adapted to be seated in the groove of the soft 65 metal piece to close the nozzle, and a nozzle tip on the outlet tube.

In testimony whereof I have hereunto set my hand, in the presence of two subscribing witnesses.

JAMES F. MACWILLIAM.
